UNITED STATES PATENT OFFICE

2,035,704

ROLL PAPER HOLDER AND CUTTER

Thomas C. Johnson, Quincy, Ill.

Application March 18, 1935, Serial No. 11,728

3 Claims. (Cl. 242—55.5)

My invention relates to certain new and useful improvements in roll paper holders and cutters and primarily has for its object to provide a holder with a simple inexpensive brake device cooperative with the saddles that support the shaft or spindle on which the paper roll is mounted; also to provide a paper cutter which after cutting off the amount of paper required will leave sufficient paper loose to take hold of so that the paper can be pulled from the roll easily in getting ready to cut the next piece of paper so that one does not have to reach up and roll the paper around by hand past the cutter before it can be taken hold of.

Other objects will in part be obvious and in part be pointed out hereinafter.

To the attainment of the aforesaid objects and ends, the invention still further resides in those novel details of construction, combination and arrangement of parts, all of which will be first fully described in the following detailed description, then be pointed out in the appended claims, reference being had to the accompanying drawing, in which:

25 Figure 1 is a plan view of the invention with a roll of paper in place, a portion of the paper roll being broken away.

Figure 2 is a vertical cross section on the line 2—2 of Figure 1.

30 Figure 3 is a detail vertical section on the line 3—3 of Figure 2.

Figure 4 is a horizontal section on the line 4—4 of Figure 2.

Figure 5 is a detail perspective view of one of the brake plates somewhat enlarged.

In the drawing, in which like numerals indicate like parts in all of the figures, 1 represents the bases on which the standards 2 are mounted. The standards 2 have their upper ends provided with outwardly extended bifurcated foot portions 3 through which bolts 4 with nuts pass to secure the standards to the bases 1 and to the top cross bar 6. The bases 1 are held spaced apart a proper distance by a cross bar 5.

45 Each standard 2 is provided with a U-shaped saddle 7 in which the ends of the paper roll shaft or spindle 27 rest.

Mounted on each standard 2 adjacent the saddles 7 are the brake devices which constitute the essential part of the present invention. Each of these devices (there is one at each side of the paper roll 25) comprises the plate 8 having a U-shaped recess 9 to straddle the saddle 7 (see Figure 2). It is also provided with a pair of side lugs 10 which project toward the standards

2 at each side of the saddle 7. Each plate 8 is also provided with a bulge 11 having a square aperture 12 to receive the bolt 14 which passes through an aperture in the standard and carries a wing nut 15, there being a coil spring 16 interposed between the plate 8 and the standard 2. The bolt 14 has a square portion which passes through the aperture 12 and a countersunk head which lies in the recess formed by the bulge 11.

Those faces 13 of the plates 8 which are opposite one another are smooth and uninterrupted so that they bear evenly on the sides of the paper roll.

By providing the recess 9 in the plate 8 and the lugs 10 to straddle the saddle 7 the plate 8 is prevented from swiveling on the axis of the bolt 14. The lugs 10 enable the plate 8 to be projected beyond the saddle 7 without disengaging the plate from the saddle.

17 and 18 designate the paper cutter which is 20 of V-shape in end elevation and is carried by a pair of arms 20 having flattened portions 19 welded or otherwise secured to the section 17 of the cutter or tear-off plate. The arms 20 are connected to a shaft portion 21 which is mounted 25 in bearing members 22 on the underside of the top cross bar 26, there being a coil spring 23 provided which constantly tends to hold the cutter plate 17—18 with its angle edge in contact 30 with the roll of paper. A hook 24 is pivoted to one side of the top cross plate 6 for the purpose of holding up the arms 20 to hold the cutter plate 17—18 away from the paper roll while inserting or removing the roll of paper or if for any other reason it be desired to hold the cutter in an inoperative position. With the construction shown and described it will be observed that when a section of paper is torn off there will be left a free end 26 which may be grasped for the purpose 40 of pulling off an additional section of paper to be torn off.

What I claim is:

1. In a paper holder, a pair of standards, bases on which said standards are mounted and a top cross connecting bar between said standards, said standards having roll-paper shaft-supporting saddles, in combination with a brake plate and tension means mounted on one of said standards adjacent its saddle, said brake plate having bifurcations to embrace said saddle as a guide and said tension means comprising a bolt with a nut passing through a standard and carrying said brake plate, and a spring on said bolt between said standard and brake plate. 50 55

2. In a paper holder, a pair of standards, bases on which said standards are mounted and a top cross connecting bar between said standards, said standards having roll-paper shaft-supporting saddles, in combination with a brake plate and tension means mounted on one of said standards adjacent its saddle, said brake plate having bifurcations to embrace said saddle as a guide and said tension means comprising a bolt with a nut 5 passing through a standard and carrying said brake plate, a spring on said bolt between said standard and brake plate, and said brake plate having a pair of guide lugs between which the saddle is located to permit said plate to be ad- 10 justed beyond the end of the saddle.
3. In a paper holder, a pair of standards, bases on which said standards are mounted, a top cross connecting bar between said standards, a bottom cross brace between said bases, said standards having roll-paper shaft-supporting saddles, 5 in combination with a paper tearoff blade of V-shape in end elevation, arms carrying said blade, means hinging said arms to said top cross connecting bar, spring means to press the angle edge of said blade against a roll of paper carried on said saddles, and a hook on said cross bar to hold said blade out of engagement with the paper when desired. 10

THOMAS C. JOHNSON. 15
